Primary Examiner — Christian P. McLean*Assistant Examiner* — Kristopher Michael Blechschmidt(74) *Attorney, Agent, or Firm* — Aird & McBurney LP(57) **CLAIM**

The ornamental design for a bearing swivel, as shown and described.

DESCRIPTION

FIG. 1 is a front elevation view of the new design for a bearing swivel, wherein the rear elevation view is a mirror image thereof;

FIG. 2 is a left side elevation view thereof, wherein the right side elevation view is a mirror image thereof;

FIG. 3 is a top plan view thereof, wherein the bottom plan view is a mirror image thereof;

FIG. 4 is a perspective view from above, to the front and to the left side thereof; and,

FIG. 5 is a perspective view from below, to the rear and the right side thereof.

1 Claim, 3 Drawing Sheets(56)
